UNITED STATES PATENT OFFICE.

WALTER F. BALCOM, OF DAYTON, OHIO.

PRESERVING-JAR.

1,342,039.

Specification of Letters Patent.

Patented June 1, 1920.

Application filed October 20, 1919. Serial No. 331,968.

To all whom it may concern:

Be it known that I, WALTER F. BALCOM, a citizen of the United States, residing at Dayton, in the county of Montgomery and 5 State of Ohio, have invented certain new and useful Improvements in Preserving-Jars, of which the following is a specification.

My invention relates to new and useful 10 improvements in preserving jars. The object of the invention is to provide efficient and simple means for sealing the lid of the jar after receiving the contents and a further object is to provide a construction whereby 15 the cap may be removed after the jar has been sealed, without obstruction from the sealing material, as will hereinafter more fully appear from the description to follow in connection with the accompanying drawings.

Referring to the said drawings in general terms,

Figure 1 is a top plan view of the jar with the lid thereon, and Fig. 2 is a vertical 25 section through the center thereof.

The jar —3— is preferably made of glass such being the most suitable material for jars of this type. The mouth or neck —4— thereof is contracted in diameter and is provided with exterior screw threads —5—. The relative diameters of the two parts of the jar, to wit, the body and the neck is such as to provide a substantial annular offset —6— between the two parts, which in 30 35 turn provides an annular channel —7— between the neck and body. The said channel —7— is inclosed by tapered walls —8— on the inner and outer sides thereof. The inner wall terminates in an inner annular shoulder —9— at the base of the neck and the outer tapered wall terminates in the annular lip —6— which extends up above the shoulder —9—. The lid or cover —1— has grooves in the inner side thereof which receive the threads —5— and the circular edge is formed in a projecting annular taper —11— with an interior shoulder —12—. The channel —7— formed as described, be-

tween the neck and the body of the jar, receives a quantity of sealing material —2— 50 which is retained therein when in soft condition, by the upwardly extended lip —6— of the jar. When the cover —1— is screwed on the neck of the jar, to close it, the edge —11— of the cover enters the sealing wax 55 —2— and the two shoulders —9— and —12— close upon a portion of the wax lying therebetween and the cover and the jar thus become thoroughly sealed. When the jar is being handled prior to placing the lid 60 thereon, the lip —6— prevents any of the wax from running out of the channel, and the construction is such that a suitable quantity of sealing wax may be placed in the channel.

Owing to the tapered character of the edge —11— of the lid, and the straight shoulder —9— and corresponding straight surface of the lid above the shoulder —9—, the lid is easily removed by unscrewing 70 without any resistance from the sealing material in the channel —7—.

Having described my invention, I claim:

A preserving jar having the neck portion thereof of such diameter relatively to the 75 body of the jar as to provide an annular channel between the base of the neck and the outer circumference of the body of the jar adapted to contain sealing material, the inner annular wall of said channel joining 80 the neck of the jar at the base thereof in a horizontal annular shoulder, and the outer annular wall of said channel terminating in an annular tapered lip which extends 85 above said horizontal annular shoulder, and a screw cap having an annular tapered edge, and a horizontal annular shoulder joining the inside of said edge at the base thereof, said edge being adapted to enter the sealing material in said channel, and said horizontal 90 annular shoulder being adapted to engage the sealing material above the inner annular shoulder of the neck, when the said cap is screwed in position on the neck of the jar.

In testimony whereof I affix my signature.

WALTER F. BALCOM.
